UNITED STATES PATENT OFFICE.

MARK C. FARR, OF CHICAGO, ILLINOIS.

LAWN-SEAT.

SPECIFICATION forming part of Letters Patent No. 696,425, dated April 1, 1902.

Application filed July 8, 1901. Serial No. 67,466. (No model.)

To all whom it may concern:

Be it known that I, MARK C. FARR, a citizen of the United States, residing at Chicago, in the county of Cook and State of Illinois, have 5 invented a new and useful Lawn-Seat, of which the following is a specification.

My invention relates to improvements in seats for lawns and campus-grounds.

The objects of my invention are to produce 10 a comfortable seat for users on lawns and at outdoor assemblies which will not injure the grass while using nor disturb the surface on which it is placed, and also to provide a portable seat which can be readily and easily carried anywhere and allow the user to be near 15 the ground and enjoy the pleasure of the close proximity to a grass-surface, flower-beds, &c., and be able to sit or recline for reading, study, sketching, fishing, and other things 20 where needed without being directly on the ground, thus obviating the chill of the earth or the stain of the grass or other substance. I attain these objects by the device illustrated in the accompanying drawings, in which—

25 Figure 1 is an elevation showing the device open and ready to use as a seat, the back B standing erect. Fig. 2 is a plan of the device as shown at Fig. 1. Fig. 3 is an elevation of the back looking from the rear, showing attachments of the brace D and hooks g g, which hold the brace when closed and ready for transportation. Fig. 4 shows the device folded for carriage.

Similar letters refer to similar parts throughout the several views.

In the drawings, A represents the front of base of my portable seat and may be constructed of any suitable material, preferably of light strong three-quarter or one inch board. 40 It should be of width of about twelve inches and of length about eighteen inches.

a is a cleat, of similar material, firmly fastened to base A, to which cleat the back B is hinged by hinges b b, so that the back may 45 be adjusted backward and forward at will. The back B is also preferably of wood and of the width of twelve inches and length twenty-four inches and about same thickness as base or seat.

50 C is the base-rest for the back, also formed of wood or other suitable material. It is about eighteen inches in length, of about three

and one-half inches in width, and is scored upon its upper side with transverse channels c, and also the base-rest is provided with vertical channels c', which are a continuation of the transverse channels c. The base-rest C is really a continuation of the base A, and it is hinged to the base A by hinges F F, which afford articulation or joint at that point, so 55 that the device may the better adapt itself to uneven ground, thus in such cases affording an adjustable and firmer base. The hinged joint also allows the folding of the seat into a small compass for transportation or carrying. D, 60 the brace or support of the back, is hinged at e e and is preferably formed of light iron or steel rod about one-fourth inch in diameter. It has a transverse bar E to engage with transverse channels c of the base-rest C, and it has 65 some vertical spurs d d to engage with the vertical channels c'.

When the device is folded, the brace D in folding will extend just far enough (see Figs. 3 and 4) to form a convenient handle to carry 75 the device and is held in place by hooks g g.

Some of the advantages of my device are as follows: The owners of lawns or parks do not like anything to be used as a seat which will cut up or destroy the grass or ground. 80

My device is operated as follows: In being placed where the user desires, opening base-rest C and extending base or seat A, laying same flat on ground, raising back B, and giving it the desired inclination by adjusting 85 brace D as desired to base-rest C, user then occupies base A, thus sitting on or near grass without incurring dampness or chill.

My device is not only useful where lawn-seats with legs are objectionable, for the reason they destroy the grass and sod, but it allows the user to be near the grass or near a bed of flowers or like situations without injury from dampness or the stain of the grass or earth. 90

These seats are useful for reading or resting, as the back can be given any desired inclination and changed from one position to another at will, as one does not like one position in sitting or lounging. They are useful 100 for naturalists, artists, and students, fishermen, and in tents, and for ranchmen and herdsmen, invalids, hospitals, sanitariums, colleges, or wherever it is desired to have a portable

seat for patients and persons, and for picnic parties and out-of-doors lectures and meetings.

What I claim, and desire to secure by Letters Patent, is—

A legless lawn-seat having a jointed or articulated base and adjustable back, a rack upon the upper side of the base-rest and a pawl attached to the back and adapted to en-

gage with the rack for adjustment, substantially as described.

In testimony whereof I affix my signature in presence of two witnesses.

MARK C. FARR.
